(57) **CLAIM**

The ornamental design for a bottle holder, as shown and described.

DESCRIPTION

FIG. 1 is a top, right, front perspective view of a bottle holder embodying our new design;

FIG. 2 is a front elevational view thereof;

FIG. 3 is a right side elevational view thereof, the left side elevational view being a mirror image of the right side shown;

FIG. 4 is a rear elevational view thereof;

FIG. 5 is a top plan view thereof; and,

FIG. 6 is a bottom plan view thereof.

The broken line representations of holes in FIGS. 1-6, of a frontal ornamentation in FIGS. 1-3, of a nozzle and associated supporting structure in FIGS. 1-4 and 6, of a receiving structure in FIGS. 1 and 3-5, of a battery receiving area cover in FIGS. 3, 4 and 6, and of supporting ribs in FIGS. 1 and 3-6, are for the purpose of illustration only, and form no part of the claimed design.

In a preferred embodiment the nature of this product is a holder for a bottle suitable to be mounted in a bathing area. In a most preferred form the holder also dispenses fluid from the bottle in an automated fashion.
